(57) **CLAIM**

The ornamental design for a charging base for cleaning appliance, as shown and described.

DESCRIPTION

The file of this patent contains at least one drawing executed in color. Copies of this patent with color drawings will be provided by the Office upon request and payment of the necessary fee.

1. Charging base for cleaning appliance

1.1 is a front view of the first embodiment of a charging base for cleaning appliance;

1.2 is a back view thereof;

1.3 is a left side view thereof;

1.4 is a right side view thereof;

1.5 is a top view thereof;

1.6 is a bottom view thereof;

1.7 is a perspective view thereof;

1.8 is another perspective view thereof;

2.1 is a front view of the second embodiment of a charging base for cleaning appliance;

2.2 is a back view thereof;

2.3 is a left side view thereof;

2.4 is a right side view thereof;

2.5 is a top view thereof;

(Continued)

2.6 is a bottom view thereof;
 2.7 is a perspective view thereof; and
 2.8 is another perspective view thereof.
 The portions covered by translucent yellow overlay in the reproductions forms no part of the claimed design.
